PRINTING EQUIPMENT FOR GUIDING
PRINTING PLATES

Walter T. Gollwitzer, Euclid, Ohio, assignor to
Addressograph-Multigraph Corporation, Wil-
mington, Del., a corporation of Delaware

Original application August 1, 1946, Serial No.
687,724. Divided and this application June 11,
1948, Serial No. 32,413

7 Claims. (Cl. 101—57)

1

This application is a division of my copending application, Serial No. 687,724, filed August 1, 1946, now Patent Number 2,576,596, patented November 27, 1951.

The present invention relates to printing equipment and more particularly to printing machines which are especially well adapted to utilize printing devices of the type disclosed in my copending application, Serial No. 32,412, filed June 11, 1948, which is also a division of my aforesaid copending application, Serial No. 687,724.

It has been customary in the past to pass printing devices through embossing mechanism to provide printing characters thereon, and then to utilize such devices in printing machines through which the devices are passed sequentially for printing such data as names and addresses of a list of customers, subscribers, and the like. A printing device, which may be simply a printing plate or a more complex unit involving other elements in addition to the plate, is usually provided for each customer, subscriber, etc. A supply of such devices is normally prepared and retained for periodical reuse. Although such printing devices and the mechanisms with which they are employed have gone into wide use and have been successful in accomplishing great savings in time and economies in various types of operations, they have nevertheless required a great deal of manual handling. Thus, in the past, it has been necessary to take each printing plate and insert it manually into a holding device for passing it through an embossing machine or the like, to form printing characters thereon. After the printing characters have been formed, it has been customary to apply the plate manually to a supporting frame which may bear an identification card, control tabs, and other material. The complete printing device, usually comprising a frame and plate assembly, is then passed through printing mechanism, particular feeding devices being required for handling such printing devices.

An object of my invention is to afford printing equipment which is adapted to utilize embossed printing plates without necessitating the use of frames, the printing equipment being constituted and arranged to hold unmounted plates positively and accurately, and to feed them into operating position in a reliable and exact manner.

An ancillary object is to enable plates of the character disclosed, in my aforesaid copending application, Serial No. 32,412 to be fed directly

2

through printing machines without assembling them with frames or carriers.

Yet another object of my invention is to so correlate printing equipment with the improved printing plate disclosed in my aforesaid copending application, Serial No. 32,412, that the advantages flowing from the improvement in the plate itself may be fully realized in the operation of the printing equipment.

10 Other and further objects of the present invention will be apparent from the following description and claims and are illustrated in the accompanying drawings which, by way of illustration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

25 Fig. 1 is a plan or face view of the preferred form of printing plate adapted to be used in machines embodying the present invention;

Fig. 2 is a view of the rear face of the plate shown in Fig. 1;

30 Fig. 3 is a sectional view of the plate shown in Fig. 1, drawn to an enlarged scale, and taken substantially along the line 3—3 on Fig. 1;

35 Figs. 4 and 5 are fragmental rear face views similar to Fig. 2 and showing modified forms of a printing plate adapted to be used in machines embodying the present invention;

Fig. 6 is a front view, similar to Fig. 1, of another form of plate adapted to be used in machines of the present invention;

40 Fig. 7 is a front elevational view of a printing machine embodying the principles of my invention;

Fig. 8 is a vertical sectional view taken through the printing plate guideway of the printing machine shown in Fig. 7;

45 Figs. 9 and 10, respectively, are detail views taken substantially on the lines 9—9 and 10—10 of Fig. 8, the scale of Fig. 10 being enlarged;

Fig. 11 is a perspective detail view of the printing plate guideway and the anvil upon which the printing plates come to rest when an impression is to be made therefrom in the printing machine shown in Fig. 7;

50 Fig. 12 is a sectional view taken substantially on the line 12—12 in Fig. 7;

Fig. 13 is a sectional view taken substantially on the line 13—13 on Fig. 12;

Fig. 14 is a sectional view taken substantially on the line 14—14 on Fig. 13; and

Figs. 15 and 16 are fragmentary sectional views similar to Fig. 13 but showing certain of the parts in operative positions different from those in which the parts are illustrated in Fig. 13.

The printing machine shown in Figs. 7 to 16, inclusive, is particularly suited for the use of unmounted printing plates of the character shown in Figs. 1 to 6, inclusive, of the drawings, these plates being described in greater detail in my aforesaid copending application, Serial No. 32,412. Plates mounted on frames, as shown, for example the Figs. 4, 6 and 8 of the aforesaid co-pending application, may of course be used in the various machines of the character, and in the manner, well known in the prior art.

However, in some cases, it is highly advantageous to be able to use unmounted plates, such as those shown in Fig. 1 hereof, by feeding them to and through printing position in a printing machine without mounting them on frames or other backing members. For certain types of work the unmounted plates are adequate without control tabs, cards, and other associated elements. When this is the case the advantages of the use of unmounted plates are obvious. They include elimination of the assembly of plates with frames, very material savings in storage space, ease of handling, and important economies to users when the purchase of frames is not necessary.

Accordingly, the machine shown in the drawings while basically similar to machines described in my prior patents, No. 1,975,318, issued October 2, 1934, and No. 1,992,661, issued February 26, 1935, is constructed and arranged to utilize plates which are unmounted and which are provided with no special guiding or holding means other than a groove G embodied in the plates, Figs. 1 to 6, inclusive.

The printing machine comprises a flat substantially rectangular table top 850 supported on four legs or posts 851 suitably connected and braced by horizontal frame members 852. The table top 850 supports, on its lower surface, a casting or bracket 853 which depends therefrom to mount a number of operating elements including a main drive shaft 854 and a short jack shaft 855. The jack shaft 855 is driven by an electric motor 856 suitably supported on frame members 852. A V-belt or the like, 857, connects a pulley 858 on motor 856 with another pulley 859 on the jack shaft 855. The shaft 855 carries a spur gear 861 which drives a spur gear 862 on the main drive shaft 854.

The main shaft 854 has secured thereto a bevel gear 863 which drives another bevel gear 864 secured to a short horizontal shaft 865 which operates a plate feeding mechanism to be described hereinafter. The shaft 854 also bears an eccentric 866, Fig. 9, which operates platen mechanism substantially identical with that described in my aforesaid prior Patent No. 1,975,318.

Near the right end of the table 850 a magazine 870 is provided for printing plates P' which are to be fed through the machine to a position beneath a platen mechanism 871. The construction so far described is substantially identical with that described in my prior Patent No. 1,992,661 mentioned above, but the feeder is particularly designed and adapted for use with plates such as those shown in Figs. 1 to 6, inclusive, hav-

ing one or more notches in at least one longitudinal edge.

The magazine 870 comprises front and rear side walls 873 and 874 and end wall members 875 and 876, respectively, at the left and right ends of the magazine, as seen in Figs. 7, 8 and 12. The end members may comprise angle or L-shaped vertical corner posts of which the front pair, not shown in Fig. 8 but indicated in Fig. 7 may be adjustably mounted, together with front wall 873, Fig. 12. Thus the magazine may be adjusted in width to accommodate plates P' of various widths. The rear side wall is fixed in accurate alignment with plate guiding and holding elements to be described hereinafter.

As best shown in Figs. 8, 13 and 15, the magazine bottom consists of a fixed plate 881 secured to the table 850 in any suitable manner. At its right end, as seen in Fig. 8, the top surface of plate 881 is cut away to provide a plurality, for example three spaced grooves 882. Grooves 882 receive a similar number of tongue elements 883 of a slideable feed plate 883 provided with depending ears 884 and mounted between a pair of guide elements 885 for rectilinear reciprocation.

The depending ears 884 are pivotally connected to a block 886 adjustably mounted on one end of a link 887. The other end of link 887 is connected as by a screw or bolt 888 to the upper end of an oscillating arm 888 pivotally supported at its lower end on a stud 889 which projects from a depending lug 891 of the casting or bracket 853.

A crank arm 892 is secured to the front end of the shaft 865 and carries a roller 893 adapted to be received in a longitudinal slot 894 of another oscillating arm 895. The arm 895 is also mounted on the stud 889 directly behind the arm 888 and normally the two are latched together by a latch lever 896 mounted on a pivot 897 on the arm 888 which engages a latch element 898 on arm 895. A spring 899 tends to hold lever 896 in engagement with the cooperating element 898.

Means are provided for unlatching the lever 896 from element 898. These means are identical with those described in my aforesaid Patent No. 1,992,661 and comprise briefly an upstanding arm 901 carried by lever 896, a roller 902 carried by the free end of a lever 903 pivoted on a stud 904, a vertically movable rod 905 having a spring 906 surrounding its upper end and bearing on lever 903, and an arm not shown carried by a rock shaft 908 having another arm 909 connected by a link 911 to a pedal lever 912. Depression of pedal 912 is effective to unlatch lever 896 from latch element 898 as described more fully in said Patent No. 1,992,661. Normally, however, the parts are latched together and each rotation of shaft 865 causes a reciprocation of feed plate 883 and feeds a plate out of the magazine.

Referring to Figs. 12 to 16, it will be noted that the rear side wall 874 of the magazine 870 is cut away to form an opening 915 to accommodate a portion of a post or stud 916 secured as by a screw 917 to the table top. The top part of the post is tapered to provide a conical element 918 so that plates placed in the magazine will have a notch or a recess element engaged with the post, to maintain them in proper alignment. A notch or groove 919 at the bottom of post 916 permits feeding out the lowermost plate only. As mentioned above, plates may be of the serpentine edge type, shown in Figs. 1 and 2, or they may be any of the types shown in Figs. 4, 5 or 6. In any case, a notch or recess in one longitudinal edge of the plate cooperates with post 916 to retain the plates

in accurately aligned relation in the magazine 870, the bottom plate only being free to be fed out of the magazine when feed plate 883 is advanced. The post 916 may be a roller, in which case the notch 919 becomes a circumferential rabbet at the lower corner of such roller.

As shown in Figs. 12, 13, 15 and 16, and as previously mentioned, the left or advance end of the feed plate 883 has the tongues 883' which ride in the notches or grooves 882 in the fixed plate 881. With the feed plate in the position shown in Figs. 12 and 13, a projecting lip element 921 on the upper part of each of the tongues 883' engages the trailing end of the bottom plate in moving to the position of Fig. 15. The feed plate 883 thus passes under the next to bottom plate P' as shown in Fig. 15. However, as movement continues to the position shown in Fig. 16, the tongues 883' ride up the cam shaped left ends 20 of grooves 882 and the lip portions 921 rise 20 above the bottom plate. Feeding movement is continued, however, by a shoulder element 922 on each tongue 883' below the lip 921, and the lip 921 thereafter rides between the bottom plate and the next higher plate, flexing the latter somewhat and serving to break up any adhesion between such next plate and plates above it. Then after the feeding plate 883 completes its feeding stroke and is later withdrawn to the right, the next plate drops into feeding position, clearing 30 the post 916 at notch 919 and subsequently the cycle is repeated.

As plates P' are fed out of the magazine, they enter between guiding and holding means which retain control over them during their movement into and out of printing position. Referring to Fig. 10, a grooved or channeled member 931, which may be integral with or separate from the table 850 but has its upper surface substantially flush therewith, is shaped to receive a guide rail 932. The rail 932 comprises a rectangular bar the lower part of which fits firmly in a groove 933 in the channel member 931. The upper front edge of the rail 932 is rabbetted as shown at 934 and a thin plate or strip 935, preferably of a resilient metal such as spring steel is fastened to the rail 932 so as to project over the rabbetted portion 934.

To the front vertical face of the rail 932 there is adjustably secured another strip 936 preferably of resilient metal, for example spring steel. The upper edge is preferably of a complementary shape to engage in a groove G' provided in the lower face of each of the plates P' near the rear edge thereof, Fig. 12. The strip 936 is notched at 50 a plurality of points, as indicated at 937, and screws 938 are passed through these notches into the rail 932. The strip 936 may thus be adjusted vertically so as to properly engage and hold plates P', in cooperation with the overlying plate or strip 935. The frictional grip on the plate should be sufficient to hold it securely and maintain it approximately in a horizontal plane.

At its right end, as seen in Figs. 8, 12 and 13, the horizontal holding strip 935 is curved upwardly as at 939 to provide a guide throat for reception of plates P' from the feed magazine. Plates P' may thus freely enter between the horizontal plate 935 and the V-edged vertical plate 936, but as they progress toward the left, the plate 935 forces them down so that the groove G' in each plate frictionally engages the sharp upper edge of vertical plate 936. As the plates P' are fed one after another, each succeeding plate advances those ahead by an amount equal to the

length of one plate. As shown in Fig. 8, there may be, for example, four plates P' between the magazine 870 and the printing position under the platen 871. Each of these plates is quite firmly held and accurately aligned by the holding elements 935 and 936, no other holding device being required. This simple plate guiding, aligning and holding mechanism, in combination with the grooved plate structure described in detail hereinabove, constitutes an important feature of my invention.

When a plate P' reaches printing position, beneath the platen structure 871, a rigid support must be provided since the plate gripping elements 935 and 936 are obviously inadequate for holding the plate for a printing impression. Hence an anvil block 940 is provided in the channel member 931, directly below the platen mechanism. Since the free longitudinal edges of plates held by the gripping elements 935 and 936 may be disposed slightly below the table level the anvil member 940 is beveled as at 941 at its right end Figs. 8 and 11, to guide the plates P' onto its supporting surface.

When a plate P' has reached printing position, where it is supported under the platen mechanism 871 by anvil block 940, a sheet or strip of paper and an inking ribbon, not shown, are disposed above the plate. As the platen descends the printing characters on the upper face of the plate P' produce an impression on the lower surface of the sheet of paper or the like in a manner well known in the art.

The platen mechanism 871 is operated by the eccentric 866 on shaft 854 in precisely the same manner as described in my aforesaid Patent No. 1,975,318. The operating structure comprises eccentric strap 951, Fig. 9, connected through link 952 to depending arm 953 of platen lever 954 pivotally mounted at 955. A spring 956 tends to hold the platen in raised position. Safety mechanism, indicated generally at 960, is provided and is identical with that described in said Patent No. 1,975,318.

45 A pedal lever 971 is pivoted on a transverse frame member as 852 and connected by a link 972 to a bail member 973 which controls a clutch mechanism 974 through a rod 975, Figs. 7 and 8. The construction and operation of such control mechanism forms no part of my present invention, being described in detail in my aforesaid Patent No. 1,992,661.

From the above description it is believed that the construction and operation of the printing mechanism will be clear. Grooved plates are fed one by one from the magazine 870 into the frictional guiding structure 934, 935, 936, each plate advancing those in front of it, to dispose such plates sequentially in printing position over the anvil block 940 and beneath the platen 871. After printing is effected, the plates are pushed on to the left to a suitable receiving compartment 980, Fig. 7, where they are preferably stacked for reuse in the same order in which they are sequentially passed through the machine.

The advantages flowing from the plate construction illustrated in Figs. 1 to 6 and described in detail in my aforesaid copending application, are thus utilized in the printing mechanism. Grooved plates may be fed and positively controlled by simple effective guiding, control and holding elements at every stage of the various operations through which such plates must be passed. The feeding mechanisms in the printing machinery take advantage of its grooved struc-

ture to maintain accurate alignment and register during movement to working position with a positive and effective holding by extremely simple mechanism during various required mechanical operations. The means whereby a plate may be securely held and controlled by engagement with a narrow longitudinal marginal portion, leaving the major part of the plate free for printing and like operations, thus constitute an important feature of my invention.

Hence, while I have illustrated and described the preferred embodiment of my invention, it is to be understood that this is capable of variation and modification and I therefore do not wish to be limited to the precise details set forth, but desire to avail myself of such changes and alterations as fall within the purview of the following claims.

I claim:

1. In a printing machine through which a succession of printing plates, each having a longitudinally extending groove formed in one face thereof along a line parallel to and removed from one edge portion thereof, are adapted to be fed, said machine comprising in combination, a magazine for receiving a supply of said plates, printing means to which said plates are to be advanced one by one, guide and holding means defining a path of movement for said plates from the magazine to the printing means, said guide and holding means comprising a horizontally extending channel means in which the said one edge portion of each of said plates is adapted to ride while the plate is being advanced from the magazine to the printing means and also comprising a member presenting a vertical edge for engaging the groove in each of said plates, and feed means for advancing the lowermost one of said plates from the bottom of said magazine accurately on to said guide and holding means.

2. In a printing machine through which a succession of printing plates, each having a longitudinally extending groove formed in one face thereof along a line parallel to and removed from one edge portion thereof, are adapted to be fed, said machine comprising in combination, a magazine for receiving a supply of said plates, printing means to which said plates are to be advanced one by one, guide and holding means defining a path of movement for said plates from the magazine to the printing means, said guide and holding means comprising flange means beneath which one edge portion of each of said printing plates may be positioned in facing relationship during advancement thereof from the magazine to the printing means and also comprising a member presenting a vertical edge for engaging the groove in each of said plates, said member being disposed beneath said flange means and spaced apart therefrom a distance slightly greater than the thicknesses of said plates whereby the said one edge portion of each of said plates may be retained against and positioned relative to said flange means while the plate is being advanced from the magazine to the printing means, and feed means for advancing the lowermost one of said plates from the bottom of said magazine accurately on to said guide and holding means.

3. In a printing machine through which a succession of printing plates, each having a longitudinally extending groove formed in one face thereof along a line parallel to and removed from one edge portion thereof, are adapted to be fed, said machine comprising in combination, a magazine for receiving a supply of said plates, print-

ing means to which said plates are to be advanced one by one, guide and holding means defining a path of movement for said plates from the magazine to the printing means, said guide and holding means comprising a flange adapted to overlie a portion of the face of each of said plates opposite to the face thereof in which said groove is disposed and also comprising means for engaging the groove in each of said plates, said last-named means being disposed beneath said flange in parallel longitudinal alignment therewith and being spaced from said flange a distance affording a passageway in which the said one edge portion of each of said printing plates may ride and be retained while the plate is being advanced from the magazine to the printing means, an anvil block having a beveled face for engaging the leading edge of each of said printing plates to properly position the same relative to the printing means, said beveled face being positioned within said path at a point in advance of the printing means, and feed means for advancing the lowermost one of said plates from the bottom of said magazine accurately on to said guide and holding means.

4. In a printing machine through which a succession of printing plates, each having a longitudinally extending groove formed in one face thereof along a line parallel to and spaced from one edge portion thereof, are adapted to be fed, said machine comprising in combination, a magazine adapted to receive a supply of said plates, printing means to which said plates are to be advanced one by one, guide and holding means defining a path of movement for said plates from the magazine to the printing means, said guide and holding means being in the form of a pair of elements in parallel longitudinal alignment one with respect to the other, one of said elements being of a configuration to engage the groove in each of said plates and the other of said elements being of a configuration to overlie a portion of the face of each of said plates opposite to the face thereof in which the said groove is disposed, said elements being spaced apart from each other a distance slightly greater than the thicknesses of said plates to thereby define a longitudinal passageway in which the said one edge of each of said plates may be held against displacement while the plate is being advanced from the magazine to the printing means, and feed means for feeding the lowermost one of said plates from the bottom of the magazine accurately on to the guide and holding means.

5. In a printing machine through which a succession of printing plates each having a notched edge adjacent the trailing edge are to be accurately aligned relative to a guide and holding means defining a path along which said plates may be advanced through the machine, which means include spaced apart channel-defining elements in parallel longitudinal alignment, one of which elements is of a configuration to engage a side portion on one face of each of said plates and the other of which elements is of a configuration to engage a groove formed in the opposite side portion on the other face whereby said plates are retained in position between said elements, a printing plate supply magazine at one end of said path, printing means to which said plates are to be advanced one by one while retained in said guide and holding means, and means for feeding the lowermost one of said printing plates from the bottom of the magazine at one end thereof in accurate position on to said guide and holding means, said last-named means comprising a

member having a portion configured complementary to the said notch in each of said printing plates and being vertically disposed within said magazine at a location corresponding to the notch in each of the plates, said portion of said member terminating short of the bottom of said magazine a distance slightly greater than the thickness of one of said plates whereby the said lowermost one of the plates alone is positionable at the bottom of said magazine free of engagement with the said configured portion, and a plate reciprocable at the other end of said magazine, said reciprocable plate being slidable along the bottom of said magazine in a direction to abut against the trailing edge of the said lowermost printing plate positionable therein free of said configured portion to feed the same on to the guide and holding means.

6. In a printing machine comprising a magazine for holding a supply of plate-like articles each having a notch formed in one longitudinal edge adjacent the trailing edge thereof, a receiving station to which said articles are to be advanced one by one, and a guideway along which said articles are to be fed one from one end of the magazine to the receiving station, feed means for advancing the lowermost one of said articles positionable at the bottom of the magazine from the said one end thereof accurately in position on to said guideway, said means comprising a member having a portion configured complementary to the notch in each of the articles and being vertically disposed within said magazine at a location corresponding to the notch in each of the articles whereby said articles may be positioned in said magazine with the notches thereof engaged by the said complementary configured portion, said complementary configured portion terminating short of the bottom of the magazine a distance slightly greater than the thickness of one of said articles but less than the combined thickness of two of said articles whereby the said lowermost one of the articles alone is positionable at the bottom of said magazine free of engagement with the said configured portion, and a plate member reciprocable at the other end of said magazine adapted to slide along the bottom of the magazine in the direction of the trailing edge of the lowermost article positionable therein to feed said lowermost article on to the guideway.

7. In a printing machine comprising a magazine for holding a supply of plate-like articles

each having a notch in one end adjacent the trailing edge thereof, a receiving station to which said articles are to be advanced one by one, and a guideway along which said articles are to be fed one by one from one end of the magazine to the receiving station, feed means for advancing the lowermost one of said articles positionable at the bottom of the magazine from the said one end thereof accurately in position on to said guideway, said means comprising a member having a portion configured complementary to the notch in each of said articles and being vertically disposed within the magazine at a location corresponding to the notch in each of the articles whereby said articles may be positioned in the magazine with the notches thereof engaged by the said complementary configured portion, said portion terminating short of the bottom of the magazine a distance slightly greater than the thickness of one of said articles but less than the combined thickness of two of said articles whereby the notch in the said lowermost one of the articles alone is not engageable with the said configured portion, a slot provided in one portion of the bottom of the magazine, said slot having a cammed end within said magazine and opening at the other end of said magazine, a plate reciprocable at the said other end of the magazine and having a leading end portion adapted to abut against that trailing edge of the said lowermost one of the articles to feed said article from beneath the said configured portion on to the guideway, said reciprocable plate being slidable along a portion of the length of the bottom of the magazine and beneath the said configured portion in the direction of the trailing edge of the said lowermost one of the articles to abut against the said trailing edge and advance said lowermost article on to the guideway.

WALTER T. GOLLWITZER.
